UNITED STATES PATENT OFFICE.

WEBSTER C. ESTES, OF BROOKLYN, NEW YORK.

DESIGN FOR A WOODEN BOX.

SPECIFICATION forming part of Design No. 25,535, dated May 19, 1896.

Application filed April 20, 1896. Serial No. 588,385. Term of patent 14 years.

To all whom it may concern:

Be it known that I, WEBSTER C. ESTES, a citizen of the United States, residing at Brooklyn, in the county of Kings and State of New York, have invented and produced a new and original Design for a Wooden Box, of which the following is a specification.

In the drawings, Figure 1 represents my design by an elevation. Fig. 2 is a vertical section, and Fig. 3 is a plan view of the same.

The general configuration of the box is round; and the leading features of my design consist in the parallel-sided portion of the cylindrical body and the annular half-round beads at the respective ends of the same, the bead at the lower end being much wider and larger than the bead at the upper end, and which parts come below the contracted neck and lip at the upper end of the cylindrical body.

The design of the cover or stopper A of the box comprises the plain horizontal top por-

tion *a*, the plain tapering sides *b*, and rounded corners *c*.

The design of the body portion B comprises the cylindrical portion with parallel sides *d* with curved contracted ends, the half-round annular bead *e* at the lower end, and the half-round annular bead *f* at the upper end of the cylindrical portion. Above the cylindrical portion the contracted portion *h* forms the neck, which is swelled or coved at the upper end to form the annular rounded lip *i*. The annular half-round bead *e* is much wider and larger than the half-round bead *f*.

What I claim is--

The design for a wooden box, substantially as shown and described.

Signed by me this 17th day of April, A. D. 1896.

WEBSTER C. ESTES.
